(57) **CLAIM**

An ornamental design for a guide for a tool, as shown and described.

DESCRIPTION

FIG. 1 is a perspective view of the guide for a tool according to the subject invention.

FIG. 2 is a top view of the guide for a tool in FIG. 1.

FIG. 3 is a side view of the guide for a tool in FIG. 1.

FIG. 4 is a side view opposite to that of the side view in FIG. 3.

FIG. 5 is an end view of the guide for a tool in FIG. 1; and, FIG. 6 is an end view opposite to that of the end view in FIG. 5.

The bottom (excluding the bolts) is flat and unornamented, and a bottom view is omitted.

1 Claim, 2 Drawing Sheets
